UNITED STATES PATENT OFFICE.

CAMDEN C. KELLER, OF YPSILANTI, MICHIGAN, ASSIGNOR OF ONE-THIRD TO THOMAS LAVIER, JR., AND ONE-THIRD TO ROY R. FISHER, BOTH OF YPSILANTI, MICHIGAN.

FLASH LIGHT.

Application filed June 18, 1921. Serial No. 478,470.

To all whom it may concern:

Be it known that I, CAMDEN C. KELLER, a citizen of the United States of America, residing at Ypsilanti, in the county of 5 Washtenaw and State of Michigan, have invented certain new and useful Improvements in Flash Lights, of which the following is a specification, reference being had therein to the accompanying drawings.

10 The invention relates to flashlights and it is the object of the invention to obtain a construction of casing which is easily manufactured and assembled and which permits of being quickly detached for the removal 15 or exchange of batteries. The invention has further reference to various features of improvement as hereinafter set forth.

In the drawings:

Figure 1 is a longitudinal section;

20 Figure 2 is a cross-section;

Figure 3 is an elevation showing the complementary casing sections.

The casing of my improved battery is formed of a plurality of complementary 25 cylindrical segments, preferably two semi-cylindrical segments A and A'. The edges of these segments are fashioned to engage each other, the one being formed with a projecting tapering tongue portion B with 30 an abutment C adjacent thereto and the other having a beveled portion D for receiving said tongue and an abutting shoulder E. The tongues B do not extend the entire length of the segment, but terminate 35 a short distance from each end and as indicated at F and G, the length between the end of the tongue and the end of the segment is different at opposite ends so that the segments can only be assembled in one 40 way. The segments are formed of any suitable material, but preferably of die castings, which are therefore accurate in form. The segments are further provided with a plurality of inwardly projecting and longitudinally extending ribs H, preferably three in number, which serve as bearings for 45 centering the battery where the latter is not of true circular shape.

To secure the segments A and A' to each other the opposite ends thereof are formed with complementary portions of a screw thread and these threaded end portions are engaged by correspondingly threaded rings

I and J. The ring J forms a cap for closing the lower end of the casing, while the ring 55 I is provided with a flange I' for engaging the lens K and clamping the same to the end of the casing. L is the reflector which is preferably formed of insulator material, such, for instance, as hard rubber and provided with an enameled or otherwise brightened inner reflecting surface. The reflector 60 is provided at its outer end with the flange L' which seats upon the end of the cylindrical segments and at the center there is 65 arranged a threaded lamp socket M for receiving the threaded bearing N of the lamp. The socket M is threaded both internally and externally and has a shoulder M' at one end for seating upon the reflector. O is 70 a metallic disk threaded to engage the outer threads of the socket and serving as a lock-nut for clamping the same to the reflector L. P is a button having a shank P' slidably 75 engaging a slot in one of the casing segments and Q is a metallic finger secured to the shank of the button and extending parallel to the casing, its outer end having the inwardly bent portion Q' adapted to contact with the disk O. 80

With the construction as described, to assemble the flashlight a battery R of any suitable construction is employed and the segments A and A' are placed around the same and engaged with each other. The cap 85 J is then screwed to the lower end of the casing and a spring S therein bears upon the bottom of the battery and yieldably presses the same upward. The reflector L, lamp socket M, lamp N and disk O being 90 first assembled with each other are then placed in as a unit with the flanges L' resting upon the upper end of the casing. This will bring the lamp in alignment with the central contact R' of the battery R and by 95 reason of the spring S, this contact is pressed into engagement with the central insulated contact of the lamp. The other terminal of the lamp is in electrical connection with the lamp socket and with the disk 10 O, but by reason of the insulating character of the reflector there is no direct electrical connection with the casing A. This casing is, however, in electrical connection with the casing of the battery both by the bearing of 105 the battery casing against the ribs H and

through the spring S and there is also electrical connection between the outer casing and the finger Q, which is controlled by the button P. Thus whenever the button is actuated to press the end Q' of the finger against the disk O, electric circuit is established which will illuminate the lamp.

An important advantage of my improved construction is that there is nothing to interfere with quickly detaching the casing whenever it is necessary to remove the battery. Also, the fact that the reflector is formed of insulating material provides a ready means of insulating the lamp socket from the casing, while the circular disk O will be in registration with the contact finger Q in any position of adjustment. Therefore, no skill is required in assembling the parts, as it is impossible to put them together in any inoperative arrangement.

What I claim as my invention is:

1. A flashlight comprising a battery, a casing formed of complementary cylindrical segments enclosing said battery, removable clamping rings for holding said segments together, a lamp unit secured by one of said clamping rings at one end of said casing and in electrical contact with one of the battery terminals, the other terminal being grounded on said casing, and a switch for grounding the other terminal of the lamp.

2. A flashlight comprising a battery, a casing formed of complementary cylindrical segments enclosing said battery and having complementary threaded end portions, a cap for engaging one threaded end of said casing sections and forming a closure, a ring for engaging the other threaded end of the casing, a lamp and lens clamped to said casing by said ring, with one of the lamp terminals in contact with a battery terminal, a spring between said cap and the opposite end of the battery for yieldably holding said contacts together and also for grounding the battery casing on the outer casing, a button slidably secured to one of the casing segments, and a finger carried by said button and movable thereby into grounding contact with said lamp.

3. A flashlight comprising a battery having a terminal contact arranged centrally at one end, an outer casing formed of complementary cylindrical segments and having complementary threaded end portions, a cap for closing one end of said casing and engaging the complementary threads thereof, a ring for engaging the opposite threaded end portions, a lamp and reflector unit seated on the end of the casing with the central lamp contact engaging the central battery contact, a lens seated on the reflector and together therewith secured by said clamping ring, a disk secured to the lamp socket and electrically insulated from said casing, a spring for holding said contacts in engage-

ment and forming a grounding connection between the battery casing and the outer casing, and a button slidably secured to one of said casing segments having a finger for forming a grounding contact with said disk. 70

4. A flashlight comprising a plurality of complementary cylindrical casing segments adapted to embrace the battery, clamping rings engaging opposite ends of said segments for holding the same together, one of said rings constituting a cap for closing the end of the casing, and a lamp and reflector unit secured by the other of said rings in operative relation to the battery. 75

5. A flashlight comprising a plurality of complementary cylindrical casing segments having their adjacent edges fashioned to engage each other and the opposite ends of said segments being provided with complementary threaded portions, threaded 80 rings for engaging the ends of said segments, one of said rings constituting a cap for closing the end of the casing and the other being flanged for engaging the lens to clamp the same to the opposite end of 85 the casing, and a lamp and reflector unit clamped by said lens in operative relation to the battery within said casing.

6. A flashlight comprising a casing for enclosing the battery, a lamp and reflector unit engageable with said casing and including a reflector formed of insulating material and flanged to engage the end of said casing, a lamp socket engaging the center of said reflector and threaded externally and internally, a disk apertured and internal threaded to engage the external threads of said socket and to form a lock-nut for clamping the same to said reflector, the internal threads of said socket being adapted to engage the threaded terminal of the lamp, permitting the central terminal of said lamp to project therethrough into contact with the battery terminal, a switch button slidably mounted on said casing, and a finger grounded upon said casing and adjustable by said button into contact with said disk to complete the lamp circuit. 100 105 110 115

7. A flashlight comprising complementary cylindrical casing segments having registering threaded portions at the ends thereof, threaded rings for engaging said threaded end portions to clamp said segments around the battery, one of said rings constituting a cap for closing one end of the casing, a spring in said cap for engaging the end of the battery to yieldably press the same upward, a reflector and lamp unit engageable with the opposite end of said casing, said reflector being formed of insulating material 120 and having the lamp socket mounted thereon and insulated thereby from the casing, a lens for closing the reflector end of the casing, said lens and reflector unit being secured by said ring, and a contact finger 125 130

grounded on said casing movable thereon into electrical connection with said lamp socket.

8. A flashlight comprising a sectional casing for enclosing the battery, a reflector, means for securing said reflector in position at one end of said casing, said reflector being formed of insulating material, a flanged socket member engaging said reflector, a lamp having a threaded terminal extending through said socket member and engaging a terminal of said battery, a disk for clamping said socket member to said reflector, a finger grounded upon said casing adapted to engage said disk, and means for actuating said finger.

9. A flashlight comprising a battery, a plurality of complementary casing segments embracing said battery, a plurality of ribs extending inwardly from said segments and engaging said battery, clamping rings engaging opposite ends of said segments and holding the same together, one of said rings constituting a cap for closing the end of said

casing, and a lamp reflector unit secured by the other of said rings in operative relation to said battery.

10. A flashlight comprising a plurality of complementary casing segments, a battery disposed between said segments, the edges of one of said segments having beveled portions intermediate the ends thereof, tongues extending from the edges of the other sections engaging said beveled portions, the distance between one end of said tongues and the adjacent ends of said segments being different from the distances between the opposite ends of said tongues and the opposite end of said segments, clamping rings engaging opposite ends of said segments for holding the same together, one of said rings constituting a cap for closing the end of said casing, and a lamp and reflector unit secured by the other of said rings in operative relation to said battery.

In testimony whereof I affix my signature.

CAMDEN C. KELLER.
